(57) **CLAIM**

The ornamental design for a measuring instrument for the calibration of torque wrenches, as shown.

DESCRIPTION

FIG. 1 is a top, front and right-side perspective view of a measuring instrument for the calibration of torque wrenches embodying my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.
